UNITED STATES PATENT OFFICE.

ALFRED LAFRANCHI, OF SNOHOMISH, WASHINGTON.

CARGO-SLING.

1,265,921.

Specification of Letters Patent.

Patented May 14, 1918.

Application filed March 28, 1917. Serial No. 157,881.

To all whom it may concern:

Be it known that I, ALFRED LAFRANCHI, a citizen of the United States, and a resident of Snohomish, in the county of Snohomish and State of Washington, have invented certain new and useful Improvements in Cargo-Slings, of which the following is a full, true, and exact specification.

My invention relates to cargo slings, and 10 more particularly to slings for use in handling logs and timbers, and has for its principal object to provide an improved and novel type of automatic load releasing sling, which releases the load when the strain on 15 the handling cable is reversed. Another object of my device is to provide means for holding the load within the sling against slipping from the sling.

Other objects will appear as my invention 20 is more fully explained in the following specifications, illustrated in the accompanying drawings and pointed out in the appended claims.

In the drawings Figure 1 is a side elevation of my device shown gripping a log. Fig. 2 is a fragmentary plan view of same taken on line $\alpha\alpha$ of Fig. 1.

Referring more particularly to the drawings, numeral 1 indicates the forward portion of a hauling line, at the end of which is secured an open hook 2. A link 3 connects the shank of hook 2 to a splice plate 4, to which is secured the end of a haul-back line 5. A sling hook 6 is secured to plate 30 4 and extends downwardly therefrom to connect with the sling proper, which includes a rigid bar 7 having an eye at either end. The eye at the upper end of the bar 7 is secured to hook 6, while one end of the 35 40 rope or cable 8 is secured to the lower end of bar 7. The other end of the cable 8 is provided with a loop 9, which may be slipped over the end of hook 2. A sliding cinch hook 10 is slidably mounted upon bar 7 and is adapted to engage line 8 in a similar manner to a snatch hook. In operation 45 the cable 8 is passed around a log 11, as shown in Fig. 1, and said cable passed through hook 10, and the end 9 hooked over end of hook 2. The sliding hook 10 is then shoved down along the bar 7 as snugly against the top of the log as possible, so that line 8 will have a tight bight against the log. The under face of sliding hook 10 is 55 provided with teeth or prongs 12, which are adapted to engage the top of the log, there-

by preventing it from slipping out of the sling. As long as the cable 1 is being drawn forward the loop 9 will stay in engagement with the hook 2, but whenever the line 1 is released and the haul-back line 5 is utilized to reverse the direction of motion of line 1, hook 2 is automatically released from engagement with the loop 9, thereby allowing the log to become released from the sling. 60 65

In logging operations and the like it is frequently desirable to release logs at a predetermined point and unless my form of automatic release is employed it is necessary to have a man stationed at this point to unfasten the log slings. My device is designed to obviate the necessity of employing this extra man. 70

While I have shown a particular form of embodiment of my invention, I am aware 75 that many minor changes therein will readily suggest to others skilled in the art without departing from the spirit and scope of the invention and I therefore desire to avoid being limited to the exact form shown and 80 described.

Having described my invention, what I 85 claim as new and desire to protect by Letters Patent, is:

1. In a device of the class described, the combination of a rigid bar, the upper end of which is secured to a haulage line and the lower end of which is secured to one end of a sling cable, an open hook secured to the haulage line, a loop on the other end of the 90 sling cable, said loop engaging the said hook, a sliding hook mounted upon the said bar and engaging the said sling cable, whereby the object may be tightly held in the loop of the sling cable. 95

2. In a cargo sling, the combination of a rigid bar having an eye at either end and secured at its upper end to a splice plate, an open hook to the eye of which is secured one end of a haulage line, a link connecting said 100 splice plate and hook, a line, one end of which is secured to the lower end of the rigid bar, and the other end of which is provided with a loop which is adapted to engage the open hook, a sliding snatch hook, 105 slidably mounted upon the said bar and adapted to engage the said sling line, downwardly extending teeth upon the under face of the said snatch hook, which are adapted to engage the object within the loop of the 110 sling, whereby the said object is prevented from engagement with the sling. 115

3. In a device of the class described the combination of a rigid eye bar, a splice plate linked to one end of said bar, an open hook linked to said splice plate, a hauling line secured to the eye of the said hook which points away from the said splice plate, a flexible cable secured at one end to the free end of the said eye bar and terminating in an open loop at the other end 10 which normally detachably engages the said hook, an open hook slidably mounted at its eye upon the said rigid bar and engaging the said flexible cable intermediate its ends, a haul back line secured to the said splice plate, whereby when the haulage line is slackened and the device is drawn by the haul back line the open end of the flexible cable is disengaged from the first mentioned hook.

ALFRED LAFRANCHI.
